UNITED STATES PATENT OFFICE.

OLAF KYLLO, OF PORTLAND, OREGON.

CLOTHES-DRIER.

1,113,169.

Specification of Letters Patent.

Patented Oct. 6, 1914.

Application filed May 26, 1914. Serial No. 841,029.

To all whom it may concern:

Be it known that I, OLAF KYLLO, a citizen of the United States, residing at Portland, in the county of Multnomah and State of 5 Oregon, have invented certain new and useful Improvements in Clothes-Driers, of which the following is a specification.

My invention relates to a class of clothes-driers that may be suspended from ceilings 10 or other overhead structures, and raised above the heads of persons standing or walking thereunder.

The object of my invention, broadly speaking, is to provide a device of this kind that 15 is simple in construction, durable, and inexpensive in manufacture, but more specifically to a device that may be easily and quickly attached to or disengaged from any superstructure, and lowered when desired 20 to hang clothes to the rods and raised to a predetermined height when the clothes are attached thereto.

With the above and other useful objects 25 in view, my invention consists of certain novel features of construction, combinations of elements and arrangements of parts to be hereinafter fully set forth and specifically claimed.

In order to fully comprehend my invention 30 and the art to which it relates, reference must be had to the following specification, taken in connection with the accompanying drawing, which forms part of this application, of which:

35 Figure 1 is a perspective of my invention with the slide raised; Fig. 2 is a similar view of the slide and rods; Fig. 3 is a detail of the lock; Fig. 4 is a vertical section through the rod holder; Fig. 5 is a cross section on line A—A, Fig. 1. Fig. 6 is a section and elevation of a modified form of my invention, and Fig. 7 a top plan view of same.

In the practice of my invention, I employ 40 a support 2, detachably fastened to body 3 by means of screws 4, while the support 45 may be attached to the ceiling or other superstructure by means of screws or bolts passing through apertures 5 in said support 50 as shown in Fig. 1. The form of body illustrated in Fig. 1 consists of two pieces of 55 wood or other material fastened at the top by means of a plate 6, and at the bottom by a rectangular collar 7; two sides of said body being open as shown in the illustrations, while the other two sides are closed. 55 Passing longitudinally of the inside of the

body, are rectangular grooves 8—8^a, to receive guides 9, 9^a, which are fastened to slide 10 and serve to prevent lateral movement of said slide. 60

A sheave 11 is attached to support 2 and a rope or cord 12, passes over said sheave and fastens to the upper end of slide 10; the free end of said cord passes downwardly to a convenient length where it may be 65 reached by the person desiring to operate the device.

A hollow cylinder 13 is inserted in collar 7 which serves as a bearing for locking-pin 14; said locking-pin being reduced at the 70 end remote from its point of contact to form a shoulder 15 against which presses one end of a helical spring 16, while the other end of said spring presses against the shoulder 17 of the cylinder. An S-shaped link 18 is 75 attached to the outwardly extending end of the locking-pin, through which passes cord 12; said cord having a knot tied therein above the link;—this allows a small amount of "slack" in the cord when the knot rests 80 on link 18, in order that the operator may move said cord horizontally to disengage locking-pin 14 from notches 19—19^a which are placed in the guide to receive said locking-pin. When the guide is lowered the 85 locking-pin automatically engages notch 19^a, and when raised and the cord released, said locking-pin automatically engages notch 19 to hold the guide to a predetermined height. 90

The structure shown in Figs. 6 and 7 95 illustrates a form of drier that is composed of metal; the body being constructed of piping, while the hub, or rod holder, is cast iron or some other cast material with a plurality of lugs 21 integral therewith; said 100 lugs serving as means to hold rods 22 in radial positions with the hub, while pins 23 serve as pivotal means on which said rods oscillate to the position shown by the broken lines 23^a. This position of the rods is 105 brought into use when the device is packed for shipping purposes, or it may be used to fold the rods when the device is not in actual use for drying purposes.

The structure of the rod holder shown in 110 Figs. 1 and 2 is substantially the same as in Figs. 6 and 7; the principal difference being the fact that the rods are detachable and do not fold up close to the body.

My invention may be constructed of any 115 material and made any size deemed suitable for all the requirements of such a de-

vice, and while I have illustrated and described a preferred form of construction and combinations of elements considered essential in materializing the same, I wish 5 to include in this application all mechanical equivalents and substitutes that may be fairly considered to come within the scope and purview of my invention as defined in the appended claim.

- 10 Having thus fully described my invention so that others skilled in the art to which it relates may be enabled to construct and use the same, what I claim and desire to secure by Letters Patent, is:—
- 15 In a device of the character described, a body portion, means to fasten said body portion to a ceiling; a slide to operate in

said body portion, means on the slide to prevent lateral movement thereof, a cord attached to said slide, means to support said 20 cord, a locking-pin to engage the slide, a link attached to said locking-pin through which said cord passes for the purpose of disengaging the locking-pin from the slide, a hub attached to the slide, and rods attached to the hubs to receive the articles to be dried, substantially as set forth.

In testimony whereof I claim the foregoing as my own, I hereunto affix my signature in the presence of two witnesses.

OLAF KYLLO.
